UNITED STATES PATENT OFFICE.

HAROLD BINNEY, OF NEW YORK, N. Y., ASSIGNOR TO THE AEOLIAN COMPANY, OF NEW YORK,
N. Y., A CORPORATION OF CONNECTICUT.

TRACKER-BOARD FOR LEGATO AND OTHER EFFECTS IN PNEUMATIC MUSICAL APPARATUS.

No. 873,981.

Specification of Letters Patent.

Patented Dec. 17, 1907.

Application filed January 13, 1906. Serial No. 295,849.

To all whom it may concern:

Be it known that I, HAROLD BINNEY, residence 10 Lexington avenue, New York city, (post-office address, 141 Broadway, New York city, New York,) have invented certain new and useful Improvements in Tracker-Boards for Legato and other Effects in Pneumatic Musical Apparatus, of which the following is a specification.

10 Some years ago it was discovered that by overlapping the perforations of successive notes of a musical composition in the perforated music rolls used for pianolas and other instruments a smoothness of sound and legato effect resembling hand-playing could be produced.

15 The object of the present invention is to get a similar result so far as possible without the use of overlapped perforations. To accomplish this I prolong each of the tracker holes in the direction of the motion of the sheet and provide means for adjusting or varying the length of opening of such tracker holes.

20 The accompanying drawings illustrate one form of the invention, Figure 1 being a face view of a portion of a tracker board provided with the present invention, omitting various other parts of the instrument which will be 25 well understood. Fig. 2 is a sectional view of the same.

The tracker board B has the mouths of the tracker ducts D elongated in the direction of travel so as to prolong the sounding of the 30 note, but the opening of these mouths is adjustable by means of a slide-plate C which has teeth like a cone that fit into and are adapted to partly close the mouths of the tracker ducts. The slide C is mounted so as 35 to be movable to more or less open the mouths of the ducts. This movement is provided for by means of screws and slots E, the upper surface of the slide plate C being flush with that of the tracker board B so as to 40 form a continuation or part thereof. Adjustment of the plate is illustrated as being

effected by means of the longitudinally movable slide G which runs beneath the slide plate C and is provided with pins H that extend up into and coöperate with inclined 50 slots J in the slide C. The lengthwise movement of slide G and pins H therefore causes the transverse movement of the slide C and decreases or increases the length of the mouths of the ducts D. To permit the 55 lengthwise movement of the slide G where the screws F extend through it it is slotted longitudinally, as shown in dotted lines.

By the use of this invention, for example on pianolas, organ music rolls designed for 60 the aeolian grand may be used on pianolas to produce legato without any change in the perforations of the rolls, the mouths of the ducts D being preferably about one-tenth of an inch longer than is at present customary. 65 This will interfere with some forms of trills unless the adjustable slide-plate C is moved to reduce the size of the ducts during the trill. When the perforated music roll is moving slowly, the mouths of the ducts should be 70 shorter than when the paper is moving rapidly.

It will be seen that the present invention furnishes one means of permitting aeolian grand music to be used on pianolas and other 75 piano players without re-cutting the rolls and at the same time without the objections that would otherwise occur in the music when used on pianolas without this invention. To some extent it provides an alternative for the use of overlapping perforations, though of course it cannot provide for all the actions that occur with the present tracker holes and appropriate pianola music.

What I claim and desire to secure by these 80 Letters Patent as the essential features of my invention are the following:

1. A tracker having duct mouths and means for adjusting their size.
2. A tracker provided with a series of 90 tracker ducts and a slide for varying the openings or mouths of the said ducts.

3. A tracker provided with a series of tracker ducts and a slide for varying the openings or mouths of the said ducts, and longitudinally moving means for adjusting the said slide.

4. A tracker provided with tracker ducts and means for varying the openings or mouths of the said ducts, said means including a comb-shaped member the teeth of which

fit into and slide in the mouths of the tracker 10 ducts.

In testimony whereof I have signed this specification in the presence of two subscribing witnesses.

HAROLD BINNEY.
